UNITED STATES PATENT OFFICE.

HARRY MARGOLIS, OF CHICAGO, ILLINOIS.

CHECK-OPERATED FEEDER FOR VENDING-MACHINES AND THE LIKE.

No. 889,628.

Specification of Letters Patent.

Patented June 2, 1908.

Application filed April 11, 1907. Serial No. 367,648.

To all whom it may concern:

Be it known that I, HARRY MARGOLIS, a citizen of the United States, residing at Chicago, in the county of Cook and State of Illinois, have invented certain new and useful Improvements in Check-Operated Feeders for Vending-Machines and the Like; and I do declare the following to be a full, clear, and exact description of the invention, such as will enable others skilled in the art to which it appertains to make and use the same.

This invention relates to improvements in check operated feeders for vending machines and the like.

15 The object of the invention is to provide a device of this character by means of which a vending machine or check operated telephone may be prevented from being operated by unauthorized parties.

20 A further object is to provide checks so constructed and arranged as to operate only the machine for which they are manufactured.

With these objects in view, the invention 25 consists of certain novel features of construction, combination and arrangement of parts as will be more fully described and particularly pointed out in the claims.

In the accompanying drawings, Figure 1 30 is a plan view of a portion of a check operated telephone box and check slot, showing the pivotally mounted check baffle arranged therein; Fig. 2 is a vertical, sectional view of the same, showing a check engaged with 35 the baffle; Fig. 3 is a similar view showing the manner in which the check is turned to permit the same to pass the baffle and enter the feed chute; Fig. 4 is a detail view of a check.

40 Referring more particularly to Figs. 1, 2, 3 and 4 of the drawing, 1 denotes a portion of a telephone box or stand, having arranged therein a check feed chute, 2, which communicates at its upper end with a check slot, 3, 45 formed in the side of the box, as shown. In the upper end of the chute, 2, adjacent to the slot, 3, is arranged a baffle, 4, said baffle being here shown in the form of an open rectangular frame which is pivoted midway between its ends upon a bolt or pin, 5, arranged across the chute 2 and having its ends mounted in the side walls of the same.

When the feed chute is provided with a

baffle constructed and arranged as herein shown and described, a specially constructed 55 check must be provided to pass said baffle plate to operate the mechanism of the machine. In Figs. 2, 3 and 4, is shown a form of check, 6, which is adapted to be engaged with the baffle, 4, and to turn with the same so as 60 to permit of the passage of the check into the feed chute, 2. The check 6 is shown as being provided in one side with a series of inwardly projecting notches, or recesses, 7, which are adapted to be engaged with the 65 opposite ends of the baffle frame, 4, and with the bolt or pin, 5, said notches allowing the check to be so engaged with the baffle frame that the latter may be turned by the check and said check thus permitted to pass 70 through the slot, 3.

While I have shown and described the baffle, 4, in the form of a rectangular pivotally mounted frame, it is obvious that said baffle may be constructed in a variety of 75 forms, and checks provided to correspond therewith, so that the check adapted for one form of baffle will not operate a different form of baffle of another machine.

From the foregoing description, taken in 80 connection with the accompanying drawings, the construction and operation of the invention may be readily understood without requiring a more extended explanation.

Various changes in the form, proportions 85 and the minor details of construction may be resorted to without departing from the principle or sacrificing any of the advantages of this invention, as defined in the appended claims.

Having thus fully described my invention, what I claim as new, and desire to secure by Letters-Patent, is:

1. In a device of the class described, a casting, a chute therein, a baffle pivotally arranged in said chute, and a check having a plurality of slots to engage different parts of the baffle and to be passed by the same into the chute.

2. A check operated feeder for vending 100 machines and the like, comprising a feed chute, a pivot bolt arranged in said chute, a rectangular baffle frame pivotally mounted midway between its ends on said bolt to obstruct the feed slot at the upper end of said 105 chute, a check having formed therein a plu-

rality of notches adapted to be engaged with the ends of said baffle frame and with the pivot bolt to turn thereon with said baffle frame and thereby pass through the slot and 5 into the feed chute, substantially as described.

In testimony whereof I have hereunto set

my hand in presence of two subscribing witnesses.

HARRY MARGOLIS.
